(57) **CLAIM**

I claim the ornamental design for a wheel rim, as shown and described.

DESCRIPTION

FIG. 1 is a top, front, right side perspective view of a wheel rim of the new design; and,

FIG. 2 is a front elevation view thereof.

The broken lines depicted in FIG. 1 and FIG. 2 are included for the purpose of illustrating a portion of the wheel rim and forms no part of the claimed design.
